DESIGN FOR A CAMERA

Chester W. Crumrine, Rochester, N. Y., assignor
to Eastman Kodak Company, Rochester, N. Y.,
a corporation of New York

Application April 8, 1936, Serial No. 62,015

Term of patent 14 years

To all whom it may concern:

Be it known that I, Chester W. Crumrine, a citizen of the United States, residing at Rochester, in the county of Monroe and State of New York, have invented a new, original, and ornamental Design for Cameras, of which the following is a specification, reference being had to the accompanying drawing, forming a part thereof.

In the drawing:

Fig. 1 is a perspective view of a camera showing my new design in a folded position.

Fig. 2 is a perspective view of the camera shown in the preceding view but in an open or picture taking position.

I claim:

The ornamental design for a camera, as shown and described.

Signed at Rochester, New York, this 2nd day of April, 1936.

CHESTER W. CRUMRINE.
